UNITED STATES PATENT OFFICE.

RAYMOND I. HILL, OF ELYRIA, OHIO, ASSIGNOR, BY MESNE ASSIGNMENTS, TO W. R. HUNTINGTON.

RESILIENT HEEL LIFT.

Application filed November 26, 1917. Serial No. 203,987.

To all whom it may concern:

Be it known that I, RAYMOND I. HILL, a citizen of the United States, residing at Elyria, in the county of Lorain and State 5 of Ohio, have invented certain new and useful Improvements in Resilient Heel Lifts; and I do hereby declare the following to be a full, clear, and exact description of the invention, such as will enable others skilled 10 in the art to which it appertains to make and use the same.

The object of my invention is to provide a resilient heel lift which when attached to a shoe heel will automatically maintain 15 closed, especially at the edges, the seam between the attaching faces of the rubber and leather sections of the shoe heel, thus avoiding the use of cement or other auxiliary attaching medium.

20 I also aim to produce a device of the character described, which in addition to accomplishing the above-named objects, is simple and convenient to make and to attach to the shoe heel.

25 These and other objects of my invention and the invention itself will be understood from a description of an embodiment of the invention.

Fig. 1 is a plan view of an embodiment of 30 my invention showing the attaching face thereof. Fig. 2 is a section taken thru the line 2—2 of Fig. 1. Fig. 3 is a section taken thru the line 3—3 of Fig. 1. Fig. 4 is a view of a heel lift embodying my invention, attached to a shoe heel. Fig. 5 is a transverse section of a second embodiment of my invention. Fig. 6 is a plan view of the attaching face of another embodiment of my invention. Fig. 7 is a vertical section thru 40 the line 7—7 of Fig. 6. Fig. 8 is a vertical section thru the line 8—8 of Fig. 6. Fig. 9 is a sectional view of the lift attached to a leather shoe heel.

Referring now to the drawing and to the 45 embodiments shown therein, at 5 is shown a heel lift made of some resilient and elastic material and having the general outline of a shoe heel. The tread face of the lift is shown at 6 and the attaching face, at 7. In 50 the embodiment shown these faces are substantially parallel to each other, though it will be apparent that they may be modified to include non-slip or cushioning devices or other expediencies, now old and well known 55 in the art. At 8 is shown a protuberance or

lug projecting from the central portion of the attaching face of the heel and in the embodiment shown, having a surface shaped like the segment of an ellipsoid.

A depression or crater 9 is formed in the 60 tread surface of the heel, which should be opposite and preferably of substantially the same outline as the protuberance 8 and opposite thereto, so that when the lift is attached to a shoe, both the protuberance and 65 the crater will be retired, leaving a substantially flat lift.

Openings are shown at 10 for the attaching 70 means, such as screws or nails. Washers 11 should be placed about these openings for the heads of the nails or screws. The openings 10 and washers 11 are placed between the apex 12 of the protuberance and the marginal edge 13 of the lift.

When the lift is attached to a shoe heel, 75 the nails or screws applied thru the openings 10 will draw the lift close against the heel of the shoe, depressing and partly compressing the protuberance 8 and straightening out the faces of the lift so that the protuberance 80 will be sprung in towards the body of the lift, and both the protuberance 8 and the crater will be retired. Owing to the resilient nature of the material employed in 85 the lift, it will always tend to regain its normal shape, shown in Figs. 1, 2 and 3. Consequently, there will always be an effort, exerted most strongly in the neighborhood of the point 12, to rotate the different sectors of the heel about the attaching devices 90 as pivots, and thereby force the marginal portions of the heel lift against the corresponding parts of the leather heel of the shoe. This effect will cause the portion 16 of the attaching face to hug very close to 95 the corresponding leather portions of the heel to which the lift is attached. As a result, the seam will not only be closed at the edge, but throughout the inter-engaging attaching surface of the leather and rubber sections of the heel.

The central portions will be maintained in close contact by the effort of the protuberance 8 to return to normal, the intermediate portions by the 100 nails or screws and the marginal portions by the effort of the protuberance to rotate the sectors of the lift about the attaching means as a pivot.

In Fig. 5 the protuberance is shown at 8', but there is no corresponding crater in the 110

tread face. The protuberance is so proportioned that any deflection caused in the tread surface when the lift is attached to a shoe heel will be so inconsiderable as to be negligible. In either embodiment, of course, there will be a certain amount of compression of the rubber in the protuberance and in the embodiment shown in Fig. 5 the protuberance 8' may be made so slight that there will be no deflection in the tread face of the lift when the lift is attached to a leather shoe heel.

In the embodiment shown in Figs. 6 to 10, inclusive, the protuberance or projection 108 comprises a net work of vertical members 50, which are composed of yielding material. As these webs 50 are made relatively thin, they yield individually and collectively. As shown in Fig. 9, when the lift is mounted on a shoe, the members 50 are compressed, and in tending to regain their normal position, they exert a force upward in the direction of the arrow p , which, acting thru the points $o o$ as a pivot, tends always to rotate the margins 131, 131 downwardly in the direction of the arrows $q q$, thereby causing the heel lift to cling closely to the leather, especially at the margins. The force with which the margins cling to the leather may, of course, be varied by changing the heights of the protuberance 108, or varying the number and size of the webs constituting the same.

It will be appreciated that the protuberance, (and where a crater is used, the crater) may be of any suitable shape and that the attaching means may be placed at any suitable position, though it will be apparent that they are best placed in such a position as to realize the greatest hugging effect at the edges of the lift.

I have shown these embodiments of my invention and the details thereof for the purpose of better describing the invention. It will be apparent that numerous and extensive departures may be made from such embodiments and details without departing from the spirit of the invention.

I claim:

1. A resilient heel lift having a flat marginal portion, and inside the marginal portion having on the attaching face a protuberance, and on the tread face a crater of substantially the same outline as the protuberance, said heel lift having means outside said protuberance for receiving attaching devices.

2. A resilient heel lift having a flat marginal portion, and inside the marginal portion having on the attaching face a convex protuberance elongated in the direction of the length of the heel, and on the tread face a concavity opposite the protuberance and of the same general outline as the latter, said heel lift having means outside said protuberance for receiving attaching devices. 65

3. A resilient heel having on its attaching face a marginal portion and inside the latter a protuberance, the thickness of the body portion of the heel being substantially as great at the protuberance as between the protuberance and the margin, and said heel having between the protuberance and the outer edge of the heel means for receiving attaching devices. 70

4. A resilient heel lift having on the attaching face a protuberance and on the tread face a crater of substantially the same outline as the protuberance, and a flat marginal surface surrounding the crater, said heel lift having means between the crater and margin for receiving attaching devices. 75

5. A resilient heel lift having on the attaching face a protuberance with a flat marginal surface surrounding it and on the tread face a crater of substantially the same outline as the protuberance, said heel lift having means between the protuberance and margin for receiving attaching devices. 80

6. A heel for shoes comprising a body portion having a substantially flat marginal portion of equal thickness throughout, and having a bulge on the attaching side of the body portion and a corresponding depression on the wearing side thereof by which the material at the bulge is substantially equal 90 in thickness at the bulge to the thickness of the body portion. 95

7. A heel for shoes comprising a body portion having a substantially flat marginal portion of equal thickness throughout, and having a bulge on the attaching side of the body portion at the middle part of the body portion with a corresponding depression on the wearing side thereof whereby the material at the bulge is substantially equal in 105 thickness at the bulge to the thickness of the body portion and adapted to be flattened out in application to a shoe whereby the tread surface will be substantially flat. 100

In witness whereof, I have hereunto signed my name this 19 day of November, 1917.

RAYMOND I. HILL.
